LOG HEATER

Mary H. Jones, 2516 Anna Way,
Sacramento, Calif. 95821

Filed Aug. 20, 1968, Ser. No. 13,210

Term of patent 14 years

Int. Cl. D23—03

U.S. Cl. D23—106

FIG. 2

FIG. 2 is a top plan view thereof; and

FIG. 3 is an end elevational view thereof as viewed from the right in FIG. 1.

I claim:

The ornamental design for a log heater, substantially as shown.
